Primary Examiner — Thomas Johannes*Assistant Examiner* — Catherine Posthauer(74) *Attorney, Agent, or Firm* — Gottlieb, Rackman & Reisman, P.C.(57) **CLAIM**

The ornamental design for a nozzle for a spraying device, as shown and described.

DESCRIPTION

FIG. 1 is a perspective view of the nozzle for a spraying device, showing my new design with its operative handle in an open position;

FIG. 2 is a front view thereof;

FIG. 3 is a top plan view thereof;

FIG. 4 is a right side view thereof, the left side view being a mirror image;

FIG. 5 is a bottom view thereof;

FIG. 6 is a rear view thereof; and,

FIG. 7 is a perspective view thereof, with the operative handle of the nozzle in a closed position of use.

The broken lines represent environmental subject matter and parts of the article that form no part of the claimed design.

1 Claim, 4 Drawing Sheets(56)
